(57) **CLAIM**

The ornamental design for a portable digital system connector, as shown and described.

DESCRIPTION

FIG. 1 is a top and side perspective view of a portable digital system connector showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is an enlarged side elevational view thereof, in use condition, showing the environment in first position;

FIG. 7 is an enlarged side elevational view thereof, in use condition, showing the environment in second position;

FIG. 8 is a front elevational view thereof;

FIG. 9 is a back elevational view thereof;

FIG. 10 is a top plan view thereof, in use condition;

FIG. 11 is another top plan view thereof, in use condition; and,

FIG. 12 is another top plan view thereof, in use condition.

The broken line in the drawing views is included for the purpose of illustrating unclaimed environment and forms no part of the claimed design.
